CABINET

Edward D. Davis, Chicago, Ill., assignor to The Eye Needle Company, Chicago, Ill., a corporation of Illinois

Application April 4, 1941, Serial No. 386,789

5 Claims. (Cl. 211—60)

This invention relates to a cabinet and more particularly to a display cabinet for articles of various types, such as for example, knitting needles, etc.

There has long been a need for a cabinet which is sturdy but which will support merchandise so prominently that it can be seen from all sides and readily examined while still in the cabinet, the merchandise being supported in such a way that the various sizes can be determined readily by the merchant or purchaser. Since there is a greater demand for certain sizes and since at times the demand changes making other sizes more sought for, it is highly important that the cabinet provide means whereby the size compartment can be readily modified by increasing or diminishing it or even entirely removing one or more size compartments without destroying the attractive appearance of the cabinet.

An object of the present invention is to provide a cabinet having the above characteristics while at the same time providing means for changing the compartment sizes, which means are barely visible and not injurious to the appearance of the cabinet. Another object is to provide a case of a certain conformation or shape which enables the articles to be displayed in stepped relation, the compartments being stepped not only in vertical order but laterally so as to expose, even from the front of the cabinet, each tier of articles displayed. A further object is to provide a cabinet of a new and important conformation which enables the cabinet to be handled securely and the products to be displayed upon a sturdy base. Other specific objects and advantages will appear as the specification proceeds.

The invention is illustrated, in a preferred embodiment, by the accompanying drawing, in which—

Figure 1 is a front view in elevation of a cabinet embodying my invention; Figure 2, a transverse sectional view, the section being taken as indicated at line 2 of Figure 1; and Figure 3, a broken transverse detail sectional view, the section being taken as indicated at line 3 of Figure 2.

In the illustration given, a cabinet 10 is illustrated which is formed of wood or any other suitable material. It will be understood that the details of construction may be modified according to the type of material used in making the cabinet. The cabinet is provided with a base 11 and a back wall 12. The inwardly curved back wall is provided with a thin veneer wall 13.

The side walls 14 taper from the rear wall forwardly and inwardly and are closed at the front end by a rearwardly inclined front wall 15. A molding base member 16 runs about the lower portion of the structure. The front wall 15 is provided with a veneer member 17.

The interior of the cabinet is divided into transverse compartments by the transverse walls 18, 19, and 20. It will be understood, of course, that any number of transverse walls may be used. In order to step the merchandise up to the desired height, I provide bottom members 20, 21 and 22 in the transverse compartment. The walls 17, 18, 19, 20 and 12 are preferably provided with spaced grooves 23 arranged in pairs facing each other and adapted to receive thin partition blades 24.

The upper face of the cabinet is curved rearwardly and upwardly as indicated by the line 25 and it will be noted that the upper face of each of the partition blades 24 is similarly curved so as to form with the cabinet an unbroken curved top surface. If desired, molding strips 26 may be secured to the top of the walls 17, 18, 19 and 20.

By having the compartments opening in stepped arrangement above each other and by employing stepped bottoms, the merchandise can be supported at the desired elevation so that they are visible. Further, by having the side walls 14 tapered inwardly as they approach the front, the rear tiers of merchandise can be seen along the sides as they project laterally beyond the forward tiers. The stepped arrangement eliminates shadows and causes the merchandise to stand out clearly. Further, there is a curved even contour of the cabinet along its top surface, in which the side walls terminate flush with the partition blades 24. It will be noted that the merchandise can be readily grasped from the side of the case and the desired pin or other article selected and withdrawn.

While the cabinet when filled with merchandise becomes quite heavy and the upwardly projecting articles cause considerable top weight, the rearwardly extended base provides a firm foundation which prevents the case from tipping. At the same time, the inwardly curved rear wall of the cabinet enables the cabinet to be, when the same is lifted, supported by one hand in the curved portion and the other at the forward corner of the base and the cabinet can be readily moved to the desired position on the counter, etc. without tipping.

The cabinet provides a minimum of structure

for supporting a great body of merchandise, while at the same time, providing an unusually firm base and display compartments which enable each tier of merchandise to receive, from any angle forward of the back wall, a full display.

The removable blades are thin but when received within the groove provide adjustable compartments of the desired sizes. The grooves which receive the blades are concealed by the blades and the grooves not in use are concealed by the merchandise. With a minimum of effort, the dealer can vary widely the size of the various compartments to suit the needs for the particular day. By terminating the blades flush with the top curved wall of the cabinet, the blades are rendered less visible and noticeable and since they do not extend beyond the upper contour of the cabinet, they do not interfere at all with the operation on the part of the customer of examining, selecting and withdrawing a knitting pin or other article.

While in the foregoing description, I have specified certain details for the purpose of illustrating the invention, it will be understood that a great number of the details may be widely varied without departing from the spirit of my invention.

I claim:

1. In a display structure of the character set forth, a casing having a wide base, a short rearwardly-inclined front wall, a relatively tall and rearwardly-inclined rear wall substantially wider than said front wall, inclined partitions dividing said casing into compartments open at their top, and side walls connecting the ends of the partitions, the front, and rear walls, with a continuous curve at the top of each side wall in which the front and rear walls are merged.

2. In a display structure of the character set forth, a casing provided with a wide base, a front wall carried by said base and tapering rearwardly, a rear wall having a concave rear surface and extending above said front wall, said rear wall being wider than said front wall, transverse partitions dividing the interior of said case into compartments open at their top, removable blades extending between said partitions for dividing

said compartments into smaller compartments, and side walls joining the ends of said front and rear walls and having a top surface providing a gradual curve between the tops of said front and rear walls, said transverse partitions terminating in alignment with the curved top of said sides and being secured at their ends to said sides.

3. In a display structure of the character set forth, a casing open at its top, a relatively narrow front wall for said casing, a relatively wide rear wall for said casing, side walls connecting the ends of said front and rear walls and tapering rearwardly and outwardly from said front wall, transverse partitions dividing the interior of said casing into compartments open at their top, the partitions being secured at their ends to said side walls, and removable blades extending between said partitions for dividing said compartments into smaller compartments.

4. In a display structure of the character set forth, a casing having a wide base, a short rearwardly-inclined front wall, a relatively tall and rearwardly-inclined rear wall, inclined partitions dividing said casing into compartments open at their top, and side walls connecting the ends of the partitions, the front and rear walls, with a continuous curve at the top of each side wall in which the front and rear walls are merged.

5. A display casing open at its top, comprising a relatively narrow and short rearwardly-inclined front wall, a relatively tall and wide rearwardly-inclined rear wall, side walls connecting the ends of said front and rear walls and tapering rearwardly and outwardly from said front wall, the upper surface of each of said side walls curving upwardly and rearwardly from the portion thereof which joins said front wall, partitions extending laterally within the casing between the side walls and secured at their ends to the side walls, partitions within said casing disposed transversely with respect to said lateral partitions, said lateral and transverse partitions providing a plurality of compartments open at their top and disposed in vertically and laterally stepped relation.

EDWARD D. DAVIS,
